(57) **CLAIM**

The ornamental design for a bottle, as shown and described.

DESCRIPTION

FIG. 1 is a front view of a bottle showing our new design, with the rear view being identical (with the exception of the phantom-line threaded portion on the neck);

FIG. 2 is a left side view thereof, with the right side view thereof being identical (with the exception of the phantom-line threaded portion on the neck);

FIG. 3 is a top view thereof; and,

FIG. 4 is a bottom view thereof.

The broken lines showing environment or structure of the bottle are for illustrative purposes only and form no part of the claimed design.
